UNITED STATES PATENT OFFICE.

CHARLES HAINES, OF CANTON, OHIO, ASSIGNOR TO THE CANTON CULVERT COMPANY,
OF CANTON, OHIO, A CORPORATION OF OHIO.

CULVERT.

1,030,298.

Specification of Letters Patent. Patented June 25, 1912.

Application filed November 13, 1911. Serial No. 659,905.

To all whom it may concern:

Be it known that I, CHARLES HAINES, a citizen of the United States, residing at Canton, in the county of Stark and State of 5 Ohio, have invented a new and useful Culvert, of which the following is a specification.

This invention relates to improvements in sheet metal culverts of the sectional, nestable or knock-down type and especially to 10 the means for connecting such sections together to form a complete culvert.

The objects of the invention are to generally improve the construction of such culverts and to provide a means for connecting the sections which is integral with such sections and is simple, strong and durable and by which a plurality of such sections can be easily and quickly united to form a substantial 15 culvert for practical use. These objects, together with other objects which will be apparent to those skilled in the art may be attained by the construction illustrated in the accompanying drawings, although the 20 invention may be embodied in other forms, the construction illustrated being chosen by way of example.

In the drawings, Figure 1 is a perspective view of a culvert embodying my invention, 30 one of the sections being removed to further disclose the construction. Fig. 2 is an enlarged, fragmentary, transverse sectional view through one of the lateral seams, showing the flanges unfastened. Fig. 3 is a similar view showing the flanges fastened by the 35 integral lugs.

Throughout the several views similar reference numerals indicate similar parts.

The complementary sections composing 40 the culvert are indicated in the drawings by the numerals 1 and 2 and may be either plain or corrugated or partly plain and partly corrugated. Circumferentially corrugated sections are commonly preferred and 45 I have so illustrated them. At its lateral seam edges each section is provided with integral, outwardly extending side flanges 3, along the marginal edges of which are the integral, spaced fastening lugs 4 disposed at 50 right angles to said flanges and directed toward the complementary section. Said flanges and lugs are preferably formed plain as shown in the drawings, although they may be corrugated if preferred, as will be 55 understood by those skilled in the art.

In arranging the sections to form a complete culvert any number of such sections may be employed to produce the desired circumference, but usually two sections only are necessary, preferably arranged as the 60 lower sections 2 and upper sections 1 in the drawing. It will be noted that the flanges 3 of the complementary sections abut, the flanges of the upper sections resting on the flanges of the lower sections. 65

The lugs 4 of each section are arranged between the similar, adjacent, spaced, oppositely disposed lugs of the complementary section, the lugs of each section thus extending beyond the flanges of the other section and being adapted to be bent over said flanges to firmly connect the sections together. For the purpose of bending the lugs 4 few and simple tools only are necessary, a hammer or a large pair of pliers may be 70 used in the manner well known to those skilled in the art, it being only necessary that the oppositely disposed lugs as in Fig. 2 be folded over and bent down upon the flanges as shown in Fig. 3. The lugs of the 75 upper sections being interposed between the lugs of the lower sections, relative endwise movement of the sections will be prevented and the lugs being of substantially the same width as the spaces between adjacent lugs, 80 the flanges 3 of the complementary sections will be engaged by the connecting means for substantially their entire length, thus producing a connection of uniform strength. 85

When the sections are provided with circumferential corrugations, as shown in the drawings, longitudinally adjacent sections should be endwise-overlapped for at least one corrugation and joints between adjacent upper sections should be arranged intermediate the joints between adjacent lower sections producing the well known break-joint construction. 90

Attention should be called to the fact that in using a culvert of my invented construction no loose or independent fastening means are necessary so that there is no possibility of losing said fastening means during transportation. The sections in themselves include the fastening means and when put 105 together and the lugs folded over the flanges a substantial, durable and thoroughly efficient culvert is produced. 100

I claim—

1. A culvert comprising complementary 110

sections having seam flanges provided with interjacent lugs folded over said flanges for fastening the sections together.

2. A culvert comprising complementary sections having seam flanges provided with integral, oppositely disposed, interjacent lugs folded over said flanges for fastening the sections together.

3. A culvert comprising complementary sections having outstanding seam flanges provided with oppositely, disposed interjacent lugs folded over said flanges for fastening the sections together.

4. A culvert comprising complementary sections having outstanding, abutting seam flanges provided at their marginal edges with integral, oppositely, disposed interjacent lugs folded over said flanges for fastening said sections together.

5. A culvert comprising complementary sections, each section having seam flanges provided at their marginal edges with spaced lugs formed integrally with said flanges, said lugs bent over the flanges of the complementary section for fastening said sections together.

6. A sheet metal culvert section provided with integral lateral flanges and integral spaced lugs extending from the marginal edges of said flanges.

In testimony that I claim the above, I have hereunto subscribed my name in the presence of two witnesses.

CHARLES HAINES.
